212 Dunview Ave., Willowdale, Ontario, Canada

Filed Apr. 18, 1963, Ser. No. 74,506

Term of patent 14 years

(Cl. D14—14)

FIG. 1.

FIG. 2.

FIG. 3.

FIG. 1 is a perspective view of a two-seat baby carriage, showing our new design with one footrest in lowered position;

FIG. 2 is a side elevational view thereof with the broken lines omitted for convenience of illustration; the opposite side being a mirror image thereof; and

FIG. 3 is a bottom plan view thereof.

The dominant features of our design reside in the portions shown in full lines.

We claim:

The ornamental design for a two-seat baby carriage, as shown and described.
